US0D1025312S

(12) **United States Design Patent** (10) **Patent No.:** **US D1,025,312 S**
(45) **Date of Patent:** **** Apr. 30, 2024**

(54) **GASKET**

(71) Applicant: **HAMILTON KENT INC.**, Etobicoke
(CA)

(72) Inventor: **Pardeep Sharma**, Brampton (CA)

(73) Assignee: **HAMILTON KENT INC.**, Etobicoke
(CA)

(**) Term: **15 Years**

(21) Appl. No.: **29/827,718**

(22) Filed: **Feb. 22, 2022**

(30) **Foreign Application Priority Data**

Jan. 31, 2022 (CA) ..... CA 210024

(51) **LOC (14) Cl.** **23-01**

CLAIM

The ornamental design for a gasket, as shown and described.

DESCRIPTION

FIG. 1 is a side front perspective view of a gasket showing the new design;

FIG. 2 is a side rear perspective view of the design shown in FIG. 1;

FIG. 3 is a front elevational view of the design shown in FIG. 1;

FIG. 4 is a rear elevational view of the design shown in FIG. 1;

FIG. 5 is a side view of the design shown in FIG. 1 with the other side view being a mirror image thereof; and,

(Continued)

FIG. 6 is a cross-sectional view taken along line 6 in FIG. 3.

1 Claim, 5 Drawing Sheets
